INVENTOR

C. H. Wigzell.

WITNESS:

Victor J. Evans

ATTORNEY

UNITED STATES PATENT OFFICE.

CHARLES HENRY WIGZELL, OF BALLINGER, TEXAS.

RADIATOR OR TANK CAP.

Application filed July 25, 1921. Serial No. 487,424.

To all whom it may concern:

Be it known that I, CHARLES HENRY WIGZELL, a citizen of the United States, residing at Ballinger, in the county of Runnels 5 and State of Texas, have invented new and useful Improvements in Radiator or Tank Caps, of which the following is a specification.

This invention relates to closures for 10 tanks, automobile radiators, and the like and has for its object the provision of a novel closure in which the use of an ordinary screw cap is avoided, my closure including a neck member adapted to be secured upon 15 a radiator or tank and further including a cap having a bayonet slot connection with the neck, the cap containing a spring-pressed sealing element whereby to prevent leakage.

An important object is the provision of 20 a device of this character which may be used in place of the ordinary neck and cap or which may be built or secured onto a tank without removing the ordinary neck thereon.

25 An additional object is the provision of a device of this character which will be simple and inexpensive in manufacture, highly efficient in use, easy to operate, durable in service, and a general improvement in the 30 art.

With the above and other objects and advantages in view, the invention consists in the details of construction to be hereinafter more fully described and claimed and illustrated in the accompanying drawings in 35 which—

Figure 1 is a side elevation of my closure device,

Figure 2 is a longitudinal sectional view 40 therethrough,

Figure 3 is a horizontal sectional view,

Figures 4 and 5 are detail views of a modified form, and Figure 6 is a detail side elevation of the neck member alone.

45 Referring more particularly to the drawings, I provide a cylindrical neck 10 preferably formed at one end with an out-turned flange 11 whereby it may be secured upon any receptacle such as a gasoline tank, radiator or the like, and this neck is provided internally with a flange 12 and is formed with a plurality of bayonet slots 13 opening out at its upper edge.

The numeral 14 designates the cap which 50 is also cylindrical and which is designed to be engaged externally upon the neck 10.

The lower edge of this cap is reinforced by a band 15 held in place by a plurality of screws 16 which extend through the band and through the cap and which project inwardly, as shown, so that they may be engaged within the bayonet slots 13. 60

Mounted within the cap 14 is a cup-shaped member 17 which has its lower end closed and adapted to seat upon a gasket 18 disposed upon the flange 12. At its upper portion the cup 17 is formed with an enlarged portion defining a shoulder 19 which is engageable with the projecting ends of the screws 16 for preventing the 70 cup from becoming disassociated from the cap. The numeral 20 designates a coil spring which is located within the cap and which has one end abutting against the closed end thereof and its other end abut- 75

ting against the closed end of the cup. In the use of my device the cup 17 is disposed within the cap 14 with the spring 20 in position, after which the screws 16 are placed in position. Assuming that the tank 80 is open, in order to close it the operator slips the cap over the neck with the screws 16 entering the entrance ends of the bayonet slots, after which the operator gives the cap a partial turn to bring the screws into the 85 closed ends of the slots whereupon the parts will be retained in this position with the lower end of the cup seating upon the gasket 18. In opening the tank the reverse operation is followed. 90

In order to adapt my device for use upon already existing radiator or tank necks, I make use of a ring 21 shown in Figures 4 and 5, this ring being provided with bayonet slots 22 corresponding to the slots 13. 95 In some instances the existing neck or radiator is internally threaded, in which event the ring 21 must be externally threaded as shown in Figure 5 and be screwed thereinto while in other instances 100 the tank neck is externally threaded, in which event the ring 21 must be internally threaded, as shown in Figure 4. The use of this form of the device is the same as the above described use. 105

From the foregoing description and a study of the drawings it will be apparent that I have thus provided a simply constructed and consequently inexpensive closure for gasoline tanks, automobile radi- 110 ators, and in fact receptacles of any kind ordinarily provided with a screw cap, my

device being so constructed and arranged that the cap may be removed and replaced in a remarkably short time and with unusual little effort.

5 While I have shown and described the preferred embodiment of my invention, it is of course to be understood that I reserve the right to make such changes in the form, construction and arrangement of parts as 10 will not depart from the spirit of the invention or the scope of the subjoined claims.

Having thus described my invention, I claim:

15 1. A receptacle closure comprising a cylindrical neck formed with bayonet slots and provided with an internally extending flange, in combination with a cap disposable exteriorly upon the neck and provided with inwardly extending projections engageable within said slots, and a spring-pressed sealing member within the cap engageable with 20 said flange, said sealing member consisting

of a cup having a closed lower end and having its upper portion enlarged to define a shoulder engageable with said projections 25 for preventing disassociation of the cup from the cap.

2. A closure device comprising a neck having an inwardly extending flange and provided with a plurality of bayonet slots, 30 in combination with a cap disposable externally upon the neck and provided with a plurality of inwardly extending projections engageable within said slots, a gasket on said flange, a cup member disposed within 35 the cap and adapted to seat upon said gasket and provided at its upper portion with an enlargement defining a shoulder engageable with said projections, and a spring located within the cap and cup for holding 40 said cup against said gasket.

In testimony whereof I affix my signature:

CHARLES HENRY WIGZELL.
